United States Patent Office.

EDWARD J. LEYBURN, OF LEXINGTON, VIRGINIA.

Letters Patent No. 104,608, dated June 21, 1870.

IMPROVEMENT IN MOTIVE-POWER FOR SEWING-MACHINES.

The Schedule referred to in these Letters Patent and making part of the same.

To all whom it may concern:

Be it known that I, EDWARD J. LEYBURN, of Lexington, in the county of Rockbridge and State of Virginia, have invented a new and improved Mechanical Movement Applicable to Sewing Machinery; and I do hereby declare that the following is a full, clear, and exact description thereof, reference being had to the accompanying drawing making part of this specification, in which—

Figure 1 is an elevation of one side of my invention, applied to the table of a sewing-machine.

Figure 2 is a similar view of the same parts, but representing them in different positions.

Figure 3 is a top view of fig. 1.

Figure 4 shows the left-hand side of the seat and its supporting-frame.

Similar letters of reference indicate corresponding parts in the several figures.

This invention relates to certain novel improvements on mechanism adapted for lessening the manual labor required to operate sewing machinery and other light machinery.

The nature of my invention consists—

First, in the application of a driving belt-wheel to a shaft, which forms the axis of an oscillating seat, the latter having the table of the sewing-machine applied to and supported by an arm extending from and moving with it, in combination with a treadle, which is connected, by rods and levers, to said wheel and seat-arm, as will be hereinafter explained.

Second, in so contriving the connection between the treadle, the movable seat-arm, and the driving belt-wheel, that, by a simple adjustment of the upper end of one of the connecting-rods, the table and seat can be rigidly fixed and motion communicated to the driving belt-wheel by means of the treadle motion, and without moving the body.

Third, in an adjustable foot-rest on the treadle, in combination with an oscillating seat, having a table applied to an arm extending from it, whereby the treadle can be adapted for large or small persons sitting in the seat, as will be hereinafter explained.

To enable others skilled in the art to understand my invention, I will explain its construction and operation.

In the accompanying drawing—

A represents a stool or stand, by which the mechanism is substantially supported.

a a, extensions of the legs of this stand, to which a treadle, T, is applied, by pivots s, and to one of which a stud, p p, is fastened, which affords a fulcrum for a connecting-rod, J.

B is a seat-frame, having applied to it, by means of springs, or otherwise, a seat, S, upon which the operator is supported while working the machine.

The back of the seat may be made elastic or rigid, adjustable or not, as circumstances require. This seat is jointed, by the standards of its frame, to a horizontal shaft or studs cast on inner side of stool uprights or bar i, on one end of which turns a driving belt-wheel, D, which also serves as a balance-wheel.

This seat-frame B is constructed with an arm, B', extending upward and forward, in such manner as to afford support to the table C on which the sewing-machine is secured. The table C, thus supported, is arranged in a convenient position to a person sitting in the seat S, and will vibrate about the axis of the shaft or bar i, with the seat and the person thereon.

Around the small wheel D' of the sewing-machine, a belt is passed, which, being carried around the driving-wheel D, will communicate rotary motion to the shaft of wheel D' when the wheel D is rotated.

Eccentrically to the outer side of wheel D a wrist-pin is applied, to which one end of a pitman, P, is attached. The other end of this pitman is pivoted to one end of a vertically-vibrating lever, L.

This lever has its fulcrum at b and at c c'. Two rods are connected to it, one of which, J, is pivoted at c to said lever, and at p to the stand A. The other rod, K, is pivoted at c' to lever L, and to a wrist-pin, m, at the outer forward corner of the treadle T.

Between the studs or pins c c', which may be adjustable, is a stud or pin, c', which may be fixed or adjustable, and which is adapted for receiving the upper end of either one of the rods J K, when it is desired to shorten or lengthen the strokes of the lever L or treadle T.

The stud b, which is fixed to the arm B' of seat-frame B, is made long enough to receive the upper end of the rod J, and, when this rod is thus adjusted, it will be seen that it will serve as a brace for rigidly holding the seat-frame when it is desired to operate the machine by the treadle T alone.

The treadle T is pivoted, at s, to the extensions a of the stand A, as above stated, so as to receive from the feet of an operator upon the seat S an oscillating motion, which motion, alone or in conjunction with a rocking motion given to the seat-frame and table, will be communicated to lever L through one or both of the rods J K, and this lever will give a rotary motion to the wheel D, which will rotate the wheel D', as above described.

For very light-running machines, the treadle may be stationary, if desired, in which case the rod J will be omitted, and the motion obtained by the action of the body upon the vibrating seat.

It will be seen, by reference to figs. 1 and 2, that a foot-stand, t, is applied to the treadle T, and that this stand can be adjusted higher or lower, in a plane parallel to the treadle, by means of the set-screws y y,

which connect the stand to post *v v*. This feature is useful in my machine, as it allows the machine to be adjusted to suit a long or a short leg.

Having described my invention,

What I claim as new, and desire to secure by Letters Patent, is—

1. The driving-wheel *D*, applied on the shaft *i*, about which the seat-frame *B* vibrates, substantially as and for the purpose described.

2. The table *C*, applied to an arm, *B'*, of the vibrating seat-frame *B*, and arranged to receive upon it mechanism which is driven from a wheel, *D*, whose axis is concentric to the axis of motion of the seat-frame and table, substantially as described.

3. The treadle *T*, applied to the fixed stand *A* of a rocking seat, in combination with the connecting-

rod *K*, lever *L*, pitman *P*, and wheel *D*, substantially as described.

4. The auxiliary rod *J*, pivoted below to the stand *A*, and adapted for being connected above, either to the lever *L* or to the fulcrum-pin *b*, substantially as and for the purposes described.

5. The combination of an oscillating treadle, *T*, and a rocking seat, in a machine which operates substantially as described.

6. The adjustable foot-stand *t*, applied to treadle *T*, and combined with a rocking seat and driving-mechanism, substantially as described.

EDWARD J. LEYBURN.
